US00D929397S

(12) **United States Design Patent** (10) **Patent No.:** **US D929,397 S**
(45) **Date of Patent:** **** Aug. 31, 2021**

(54) **RECORDING AND DATA STORAGE MEDIA DEVICE**

(71) Applicant: **SONY INTERACTIVE ENTERTAINMENT INC.**, Tokyo (JP)

(72) Inventor: **Yujin Morisawa**, Tokyo (JP)

(73) Assignee: **SONY INTERACTIVE ENTERTAINMENT INC.**, Tokyo (JP)

(**) Term: **15 Years**

(21) Appl. No.: **29/696,514**

(22) Filed: **Jun. 28, 2019**

(30) **Foreign Application Priority Data**

Dec. 28, 2018 (JP) 2018-028852

(51) **LOC (13) Cl.** **14-02**

(52) **U.S. Cl.**

USPC **D14/348**

(58) **Field of Classification Search**

USPC D14/348, 356-357, 363, 365, 367,
D14/433-435, 436-437, 443, 480.1,

D14/480.7, 484.1, 125, 135, 167, 172,

(57) **CLAIM**

The ornamental design for a recording and data storage media device, as shown and described.

DESCRIPTION

FIG. 1 is a perspective view of front, top and left side of a recording and data storage media device showing my new design;

FIG. 2 is a perspective view of rear, top and right side thereof;

FIG. 3 is a perspective view of front, bottom and right side thereof;

FIG. 4 is a perspective view of front, bottom and right side thereof;

FIG. 5 is a perspective view of front, bottom and right side thereof;

FIG. 6 is a front view thereof;

FIG. 7 is a rear view thereof;

FIG. 8 is a left side view thereof;

FIG. 9 is a right side view thereof;

FIG. 10 is a top view thereof; and,

FIG. 11 is a bottom view thereof.

1 Claim, 9 Drawing Sheets
